[57] **CLAIM**

The ornamental design for a biochemical card for use in automated microbial machines, as shown and described.

DESCRIPTION

FIG. 1 is a front elevational view of a biochemical card for use in automated microbial machines showing our new design;

FIG. 2 is a rear elevational view thereof;

FIG. 3 is a side elevational view thereof;

FIG. 4 is a side elevational view thereof, opposite that shown in FIG. 3;

FIG. 5 is a top plan view thereof; and,

FIG. 6 is a bottom plan view thereof.

1 Claim, 3 Drawing Sheets

FIG. 1**FIG. 2**FIG. 3

FIG. 4

FIG. 5

FIG. 6
